UNITED STATES PATENT OFFICE.

FREDERICK JOHN BIEL AND JOSEPH SELVESTER URBAN, OF TERRE HAUTE, INDIANA; SAID URBAN ASSIGNOR TO SAID BIEL.

WRENCH.

SPECIFICATION forming part of Letters Patent No. 443,216, dated December 23, 1890.

Application filed February 13, 1890. Serial No. 340,317. (No model.)

To all whom it may concern:

Be it known that we, FREDERICK JOHN BIEL and JOSEPH SELVESTER URBAN, of Terre Haute, in the county of Vigo and State of Indiana, have invented certain new and useful Improvements in Wrenches; and we do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to certain improvements in wrenches.

The object of the invention is to produce an improved, cheap, simple, and exceedingly strong and durable wrench which can be easily and quickly adjusted to grasp variously-sized pipes, and is composed of a minimum number of strong and durable parts. These objects are accomplished by and this invention consists in certain novel features of construction and in combinations of parts more fully described hereinafter, and particularly pointed out in the claim.

Referring to the accompanying drawings, Figure 1 is a front edge elevation of the wrench. Fig. 2 is a side elevation of the same. Fig. 3 is a rear edge elevation. Fig. 4 is a cross-section on the line $x-x$, Fig. 3.

In the drawings, the reference-letter a indicates the straight wrench-bar. This bar is preferably made integral, with one end forming the handle b of the wrench, while the opposite end of the wrench-bar forms the rigid jaw c of the wrench. This rigid jaw c is formed by a head on the end of the wrench-bar and preferably integral with the same.

40 The contact or upper face d of this jaw is smooth and inclined downwardly from the rear edge or end of the jaw toward the front edge thereof, as clearly shown in Fig. 2, and at a suitable angle.

45 The reference-letter e indicates the movable or adjustable jaw of the wrench located over and adjustable toward or away from the rigid jaw. This jaw e is provided and formed integral with a straight shank f , which is loosely and longitudinally confined on the rear edge

of the wrench-bar. The jaw e is strongly constructed and extends forwardly and at right angles from the upper end of the shank over the rigid jaw. The under or contact face of this movable jaw is straight or extends in a 55 plane at right angles to the axis of the wrench-bar and shank, and this contact-face is provided with sharp transverse projecting teeth or serrations g , inclined downwardly and inwardly in a direction opposite to the inclination of the rigid jaw.

A strong heavy U-shaped metal strap h has its ends strongly secured on opposite sides of the wrench-bar just below the rigid jaw by one or more strong rivets i , and loosely embraces the shank of the movable jaw and confines the same on the rear edge of the wrench-bar, allowing the shank a free longitudinal slide thereon. At its rear or lower end the shank is provided with a swinging yoke or 70 clevis pivoted thereto and embracing the wrench-bar. This yoke consists of the two strong plates or links j , located on opposite sides of the wrench-bar, and at their corresponding ends pivoted to the rear end of said 75 shank, preferably by a single pivot-pin k , passed transversely through said shank. The opposite and free ends of said links are rigidly connected by a rod or bar l , extending transversely across the front edge of the wrench-bar. This yoke extends diagonally from the lower end of said shank downwardly and forwardly, so that when the free end of the yoke is swung outwardly its bar l will pass out from engagement with said front edge. The front 80 edge of the wrench-bar is provided with a series of sockets or depressions, forming the series of downwardly-curved teeth m , formed to receive the bar l of the yoke and hold the same against upward pressure. The free end 85 of the yoke is held down and the bar l in engagement with one of said teeth by the plate-spring m' , having a head n at one end rigidly secured to the shank of the movable jaw, so that the free end of said spring will bear 90 against the upper edge of one of the links j , and thereby yieldingly hold the said yoke down, as is clearly evident.

The operation of the wrench will be clearly understood from the drawings and following 100

remarks: The jaw can be quickly and easily set to grasp a pipe of almost any size by grasping the handle end of the wrench-bar with one hand and pressing down on the swinging yoke 5 with the thumb and forefinger thereof until the bar *l* of said yoke is free from the ratchet-teeth of said bar, and then with the other hand moving the adjustable jaw in or out the desired distance and releasing the swinging 10 yoke, which will immediately spring back into position with the bar *l* in engagement with one of the ratchet-teeth of the wrench-bar, whereby the jaws will be held in that adjustment. The pipe to be turned is located between 15 the jaws when the wrench is applied thereto, and when downward pressure is exerted on the bar the smooth inclined face of the rigid jaw draws the teeth of the movable jaw tightly into the pipe and tightly binds the pipe into the V-shaped recess between 20 said jaws. By means of this peculiar construction great twisting pressure can be exerted on the pipe with a minimum amount of strain on the parts of the wrench. The fulcrum for the wrench-bar is its rigid jaw bearing on 25 the side of the pipe and the twisting force being applied to the pipe by straight-faced serrated jaw, and the greater the downward pressure on the wrench-bar the tighter the inclined jaw wedges the pipe into the opening 30 between the jaws and the serrated jaws against

the pipe. The wrench cannot slip on the pipe, and by reason of the smooth inclined face the wrench is released the moment the pressure ceases, and there is no sticking or trouble in 35 loosing the wrench from the pipe.

What we claim is—

In a wrench, the combination of a lever-bar provided with an inclined jaw, holding-notches along the inner side, and the rigid guide-loop 40 adjacent to said jaw, the sliding jaw working in said loop, the clevis pivoted to the shank end of the sliding jaw adapted to engage the holding-notches of the lever-bar, and the spring secured to the shank of the sliding 45 jaw between the guiding-loop and the clevis adapted to hold the clevis to the notches when the wrench is not in use, the arrangement of the parts being such that the pull on the sliding jaw during the working of the wrench 50 aids in retaining the parts in their operative position, said parts being constructed and arranged substantially as described.

In testimony that we claim the foregoing as our own we affix our signatures in presence of 55 two witnesses.

FREDERICK JOHN BIEL.
JOSEPH SELVESTER URBAN.
